UNITED STATES PATENT OFFICE.

CECIL M. WICKSTRUM, OF OMAHA, NEBRASKA.

KNEELING BENCH.

Application filed April 6, 1928. Serial No. 267,896.

This invention has reference to burial furniture usually supplied at funeral services, by the undertaker, the primary object of the invention being to provide a kneeling bench 5 to be positioned adjacent to the coffin so that the mourners may kneel in prayer before the coffin.

Another object of the invention is to provide a device of this character which may be 10 readily folded into a small and compact article for transportation, and one which may be extended to its active position, with facility.

A still further object of the invention is to provide a device of this character wherein the 15 case in which the pads or cushions are held, forms the support for the bench when the kneeling bench is in its extended position.

With the foregoing and other objects in view, which will appear as the description 20 proceeds, the invention resides in the combination and arrangement of parts and in the details of construction hereinafter described and claimed, it being understood that changes in the precise embodiment of the invention 25 herein disclosed, may be made within the scope of what is claimed, without departing from the spirit of the invention.

Referring to the drawings:

Figure 1 is a perspective view illustrating 30 the kneeling bench as in its extended position.

Figure 2 is a perspective view of the bench when closed.

Figure 3 is a transverse sectional view 35 through the kneeling bench when in an extended position.

Figure 4 is a vertical sectional view through the kneeling bench.

Figure 5 is an enlarged fragmental sectional view illustrating one of the fastening devices, the same being taken on line 5—5 of Figure 4.

Figure 6 is an elevational view of the kneeling bench in its open position prior to the 45 moving of the cushions or pads to their active positions.

Figure 7 is a vertical sectional view through the device when folded for carrying.

Figure 8 is an enlarged detail view of one 50 of the hinges.

Referring to the drawings in detail, the device includes a pair of box-like sections, hingedly connected as by means of the hinges 5 and 6 arranged at the upper and lower edges thereof.

Each of these sections has an open side so

that when the sections are moved together the sections will provide a casing.

The sections are indicated generally by the reference characters 7 and 8 respectively, and 60 as shown, each section is provided with a supporting bar 9 arranged in spaced relation with the lower end of the section, as clearly shown by Figure 4, the supporting bar 9 being provided with a recessed portion 10 defining a shoulder to receive the inner edge of the movable knee rest 11 which is connected with the member 9 by means of hinges 12, so that the knee rest 11 may be folded from a position as shown by Figure 7, to its extended 65 position as shown by Figure 4, the shoulder relieving the hinges 12 of undue strain. 70

The upper surface of the knee rest is supplied with a cushion 13 for the comfort of the user. The reference character 14 indicates a supporting member which is hingedly connected to the under surface of the knee rest 13 at a point adjacent to the outer edge thereof and is adapted to swing downwardly to a position as shown by Figure 4 to support 75 the outer edge of the knee rest. Secured to the member 14 is a hook member 15 adapted to hook over the headed bolt 16, secured to the inwardly foldable side section 17, to secure the member 14 in an upright position at 80 all times. 85

The reference character 18 designates an elbow pad which is of a width equal to the width of one of the ends of the casing, the same being covered by the cloth covering 90 19, and secured under the end of the section supporting the same, so that it will swing upwardly and rest on the upper edge of the casing, when the device is used as a kneeling bench. 95

A suitable covering is permanently secured to the inner surfaces of the casing, and to the outer and inner surfaces of the movable end members 17, the coverings of the end members having loose extensions 19' that fit over 100 the outer ends of the sections 7 and 8 to cover them, the upper portions of the extensions 19' being held under the elbow pads 18, so that all of the elements of the kneeling bench will be covered to lend a pleasing appearance 105 to the device.

A latch indicated at 20 forms a part of the hinge 6, and is adapted to move to a position as shown by Figure 8, to lock the sections of the kneeling bench in their extended positions. 110

From the foregoing it will be seen that due

to the construction shown and described, the knee rests may be folded from a position as shown by Figure 4 and the elbow pads may be swung inwardly, whereupon the sections 17 5 may be swung to overlie the knee rest and elbow pad and the sections may be moved to their closed positions.

It will be also be obvious that the device 10 may be readily moved from its closed position to its extended position with facility, and that when the device is in its closed position it may be readily carried from place to place.

It might be further stated that fasteners 15 such as indicated at 21 are provided to hold the sections in their closed positions.

I claim:

1. A kneeling bench including a pair of hingedly connected sections, a knee rest 20 forming a part of each section, an elbow pad forming a part of each section, said knee rest and elbow pad adapted to be swung to a position to be housed by the section, and means for holding the sections in their open positions.

2. A kneeling bench including a pair of 25 box-like sections, knee rests, hinges for con-

necting the knee rests within the sections, elbow pads carried by the sections and adapted to normally swing to position within the sections, means for supporting the knee rests in their active position, and inwardly movable end pieces for engaging the outer ends of the knee rests when the knee rests are in their extended positions.

3. A portable kneeling bench including a body portion, formed of pivotally connected box-like members, a wide pivoted member in each of the box-like members and adapted to swing outwardly defining a knee rest, and means for supporting the wide pivoted members in their extended positions.

4. A portable kneeling bench including pivotally connected sections, a knee rest secured within each section and adapted to swing outwardly to a horizontal position, means for supporting the knee rests in their active positions, and an elbow pad connected with each section and adapted to swing outwardly to overlie the upper end of each section.

In testimony that I claim the foregoing as my own, I have hereto affixed my signature.

CECIL M. WICKSTRUM.
